US00D576636S

(12) United States Design Patent
Wong et al.

(10) Patent No.: US D576,636 S
(45) Date of Patent: * Sep. 9, 2008

(54) PLAYER

(75) Inventors: Shih-Fang Wong, Taipei Hsien (TW);
Chung-Yuan Chen, Taipei Hsien (TW);
Jing Liu, Shenzhen (CN)

(73) Assignee: Hon Hai Precision Industry Co., Ltd.,
Tu-Cheng, Taipei Hsien (TW)

() Term: 14 Years

(21) Appl. No.: 29/295,894

(22) Filed: Oct. 10, 2007

(30) Foreign Application Priority Data

Sep. 5, 2007 (CN) 2007 3 0201048

(51) LOC (8) Cl. 14-03

(57) CLAIM

The ornamental design for a player, as shown and described.

DESCRIPTION

FIG. 1 is a top, front, and right side perspective view of a player showing our new design;

FIG. 2 is a front elevational view thereof;

FIG. 3 is a rear elevational view thereof;

FIG. 4 is a left-side, elevational view thereof;

FIG. 5 is a right-side, elevational view thereof;

FIG. 6 is a top plan view thereof; and,

FIG. 7 is a bottom plan view thereof.

The broken lines, which define the bounds of the claimed design, form no part thereof. The broken lines environmental are for illustrative purpose only and form no part of the claimed design.

1 Claim, 7 Drawing Sheets
